ALEXANDER B. B. HARRIS, OF RICHMOND, VIRGINIA

COMBINATION HOSE REEL AND SPRINKLER

Application filed October 21, 1930. Serial No. 490,309.

This invention relates to improvements in apparatus for directing streams of water, and it consists of the constructions, combinations and arrangements herein described and claimed.

An object of the invention, which for the purpose of illustration of its principles is embodied in a hose reel of a familiar type, is to so combine the nozzle of a hose with the reel from which the hose is first unwound that the reel will hold the nozzle at any selected adjustment and throw the stream of water in the desired direction.

A further object of the invention is to utilize the ordinary household hose reel both as a device on which to wind the hose when not in use and as a means for adjustably holding the hose nozzle in selected positions so that the stream of water can be directed where desired when the hose is in use.

A further object of the invention is to enable the combination of a hose reel of any type with the nozzle or mouthpiece of the hose adapted to be wound thereon, so that said reel can be made to play the double part already pointed out.

Other objects and advantages will appear in the following specification, reference being had to the accompanying drawing in which:

Figure 1 is a side elevation of a familiar type of hose reel, illustrating the combination therewith of the nozzle after the hose has been unwound and attached to a water outlet (not shown).

Figure 2 is a front elevation of the hose reel, a part being shown in section.

Figure 3 is a detail vertical section taken on the line 3—3 of Figure 1.

Figure 4 is a horizontal section taken substantially on the line 4—4 of Figure 3, parts being shown in elevation.

Figure 5 is a detail view illustrating a modified type of clamping device.

The more or less familiar hose reel illustrated in Figures 1 and 2 comprises a frame 1, which for the purpose of this disclosure is regarded as a base, and the drum 2 which together with its guiding or retaining arms 3 is regarded as the movable member. The

movable member 2, 3 is pivoted on the frame as at 4, and it is upon this pivot that the movable member turns both for the purpose of coiling the hose 5 when not in use and adjusting the nozzle 6 to various elevations when the hose is in use.

To the latter end provision is made of a clamping device 7 by which attachment of the hose and nozzle with the hose reel is made. The clamping device may partake of any one of a variety of forms, but the ones selected for illustration herein comprise a block 8 (Figures 3 and 4) with a nipple 9 of which the nozzle 6 is an integral part, and a threaded recess 10 at the other side with which the end of the hose 5 is coupled. Water from the hose 5 flows through the bore 11 and thence out of the nozzle 6.

A slot 12 (Fig. 4) in a lateral enlargement 13 of the block 8 receives one of the arms 3 whereupon a set screw 14 is screwed home in order to temporarily affix the clamping device to the arm of the reel. Should it be preferred to use a wedge in lieu of the screw 14 it is intended that such substitution shall be within the scope of this disclosure.

Another and somewhat simpler form of clamping device comprises a member 15 (Fig. 5) which, in effect, is a band that will be slid over the end of one of the arms 3 and then fastened by a set screw 14 as before. This member 15 has a pendent hook 16 in which either the hose or a part of the nozzle may be rested as denoted by 17, the small end 18 of the hook extending up high enough to enable the insertion of a retaining pin 19 on a bias. The end 18 obviously has an angled hole for the purpose, and when the pin is inserted its head 20 will bind against the hose or nozzle and thus hold the latter with necessary firmness.

It is even possible to reduce the factor of clamping of the hose or nozzle to simpler terms by pressing the hose holder 21 into service. This hose holder is customarily of U-shape, is permanently affixed to one of the arms 3 and has a resilient quality in which respect it too is a clamping device. The hose or nozzle, again denoted by 17, may be in-

serted in the holder 21 for the purpose of directing the water stream where desired.

Thus far it is clear that the discharge end of the hose is to be attached in one way or another to the ordinarily movable member of a conventional reel. But the movable member must be prevented from movement during such attachment and during the sprinkling operation otherwise the stream

10 could not be directed to desired spots as herein contemplated. The purpose is accomplished by using a wedge 22 in conjunction with the frame 1. This is simply a bent piece that fits around one side of the frame about as shown, and is capable of being slid down between the frame and the rim of the drum 2 so as to bind the latter wherever set.

It will be understood without minute explanation that with the nozzle once slipped 20 upon the arm 3, the user has only to turn the drum 2 in one direction or the other to incline the nozzle 6 in any position whatsoever within a compass of 180°. Having set the nozzle it only remains to force the wedge 22 home

25 when the water will be directed to the given spot until other vertical adjustment is desired. Horizontal adjustments in the direction of the water stream are made by simply flipping the hose 5 to one side or the other.

30 The hose being flexible permits turning of the hose reel upon those parts that rest on the ground.

The operation is readily understood. Considering the form in Figures 1 and 2, the 35 user will unwind the hose 5 and attach one end to the water outlet. The clamping device 7 will be slipped over one of the arms 3 and fixed in position by the set screw 14. The drum 2 is next turned until the nozzle 6 assumes the desired inclination, whereupon the 40 wedge 22 is pushed in between the rim of the drum 2 and the adjoining side of the frame 1 whereupon the adjustment will be completed.

Upon later desiring to change the vertical 45 angle of discharge it is only necessary to turn the drum in reference to the wedge 22, the friction between the two being of sufficiently low degree to permit the easy movement. Horizontal adjustments are made by simply 50 laying the hose 5 in a slightly different position, when the entire reel will correspondingly adapt itself. This description can be read in connection with any of the remaining types of clamping devices in Figures 5 and 2.

55 I claim:—

1. In a hose reel having a base and a freely movable member for storing the hose when not in use, a clamping device for attaching a hose nozzle to the movable member in a 60 sprinkling position, and means engageable with the base and movable member to stop the movement of said member and hold the latter at relative adjustments.

2. In a hose reel having a base and a 65 freely movable member for storing the hose

when not in use, a clamping device for attaching the nozzle of a hose to a part of the movable member in a sprinkling position, and a wedge insertable between a part of the base and the movable member to prevent movement of said member and to hold the nozzle at a desired inclination.

3. In a hose reel having a base and a revolute drum with hose retaining arms, a clamping device for attaching the discharge end of a hose to one of the arms to hold the nozzle in a sprinkling position, and means insertable between a part of the base and an adjoining rim of the drum to keep the latter from revolving.

4. In a hose reel having a base and a revolute drum with hose retaining arms, a clamping device for attaching a hose and nozzle to one of the arms, said device comprising a block having a bore to the ends of which the hose and nozzle are coupled, and a slotted enlargement receiving said arm, and means to secure said arm and block; and means insertable between the rim of the drum and a part of the base.

5. In a hose reel, a movable member including a drum with a hose retaining arm, a member fitted upon the arm having means to secure the member in position, a hook carried by said member to receive a portion of a hose, means inserted through part of the hook to engage the hose and retain it in the hook, a base respecting which the member is movable, and means engageable with the base and member to hold the member at relative adjustments.

6. In a hose reel having a base, a movable member for storing the hose when not in use, means to adjust said member to various positions in reference to the base, a clamping device for attaching a hose to said movable member, said device comprising a hook defining recess, said hook having an angled hole, and a pin insertable in the hole to extend at an inclination over the recess to retain a hose 11 inserted in the recess.
